[57] CLAIM

The ornamental design for a fireplace grate and blower tube surround assembly, as shown and described.

DESCRIPTION

FIG. 1 is a front perspective view of the fireplace grate and blower tube surround assembly, viewed from above and to the front of the assembly, illustrating my new design;

FIG. 2 is a rear elevation view thereof, viewed from above and to the rear thereof;

FIG. 3 is a front elevation view thereof;

FIG. 4 is an end elevation view thereof, viewed from the right of FIG. 3, the opposite end elevation being substantially the mirror image thereof;

FIG. 5 is a top plan view thereof; and

FIG. 6 is a rear view thereof.
